UNITED STATES PATENT OFFICE.

GEORGE P. A. WEISENORN, OF QUINCY, ILLINOIS.

WIRE-FENCE MACHINE.

SPECIFICATION forming part of Letters Patent No. 653,719, dated July 17, 1900.

Application filed June 14, 1899. Serial No. 720,534. (No model.)

To all whom it may concern:

Be it known that I, GEORGE P. A. WEISEN-
BORN, a citizen of the United States, residing
at Quincy, in the county of Adams and State
5 of Illinois, have invented certain new and use-
ful Improvements in Wire-Fence Machines;
and I do declare the following to be a full, clear,
and exact description of the invention, such
as will enable others skilled in the art to which
10 it appertains to make and use the same.

My invention relates to certain novel im-
provements in wire-fence-weaving machines;
and the object is to simplify and improve the
construction and increase the durability,
15 range, and efficiency of the device.

To this end the invention consists in cer-
tain features of construction and combina-
tion of parts, which will be hereinafter more
fully described, and particularly pointed out
20 in the appended claims.

In the accompanying drawings the same
reference characters indicate the same parts
of the invention.

Figure 1 is a front view of my improved wire-
25 fence-weaving machine as it appears in oper-
ation. Fig. 2 is a side elevation, parts being
broken away. Fig. 3 is a vertical section, on
an enlarged scale, of a portion of my machine.
Fig. 4 is a detail side view of one of the twis-
30 ter-heads. Fig. 5 is a similar view of the other
side. Fig. 6 is a detail view of the guide-
guard 18. Fig. 7 is a fragmentary view of the
rear of the bevel-gear 8, showing the locking-
recess 8'.

35 1 1 denote parallel plates, which are prac-
tically counterpart members, and they are
laterally stiffened by the truss-braces *a a*.
These plates and braces are secured together
at their ends, and the plates are secured
40 throughout their length by a series of bolts
2 2 and intervening stay-sleeves 3 3. These
plates are provided with alined orifices to re-
ceive the twister-heads 4 4', all of which are
uniform in construction and each is cast with
45 a circumferential gear 4², the gear on the one
intermeshing with the contiguous gears
throughout the entire series, so that a rotary
motion imparted to one will impart a corre-
sponding movement to the entire series with
50 the alternate gears revolving in the same di-
rection. These twister-heads are each pro-
vided with a diaphragm 4³, formed with trans-

verse heart-shaped orifices 4⁴ to receive the
contiguous strands 5 5 of the horizontal fence-
wire and with an intervening web 6 to 55
strengthen the metal between the orifices.
Each twister-head is formed with the bear-
ings 4⁵ and 4⁶, which are journaled in the ori-
fices in the plates, and with the annular shoul-
ders 4⁷ 4⁷, which retain the head in aline- 60
ment. The rear end of each head is also
formed with an annular shoulder 4⁸ and a con-
crete flange 4⁹, the periphery of which is
formed with a rectangular radial lug 4¹⁰, and
the inner face of the flange is also provided 65
with longitudinal lugs 4¹¹ 4¹² to receive the
countersunk screws 7 7, which secure the
bevel gear-wheel 8 to the head 4', the bevel-
gear being provided with a recess 8' to receive
the lug 4¹⁰ and thus take the strain from the 70
retaining-screws.

9 denotes a bevel-pinion in mesh with the
gear 8, and it is fixed on a shaft 10, journaled
in the angular bracket 12, fixed to the plate 1,
and the outer end of said shaft carries a 75
crank-handle 13, by means of which a rotary
motion is simultaneously imparted to the
twister-heads.

14 denotes an adjustable foot-gage secured
between the lower ends of the plates to form 80
a support for the stay-wires in the operation
of building the fence.

15 15 denote conveying brace-rods, the outer
ends of which are adjustably secured in a
socket 16 by the set-screws 17 17, and this 85
socket in turn is adjustably secured to an
angle-iron guide or guard 18 by means of a
set-screw 19, which passes through a slot 20
in said guard. This guard is also provided
with guide-orifices 21 21 to receive the hori- 90
zontal fence-wires, and thus support the ma-
chine in a vertical position.

22 denotes the tension devices, which re-
tain the horizontal wires in position while
the fence is being formed, and 23 denotes the 95
spreaders, which separate the contiguous
strands 5 5 of the fence-wires in advance of
the machine.

The operation of the machine is as follows:
The fence-wires are arranged in pairs, as 100
shown, the strands of each pair passing
through the proper twister-head, as shown,
and after a few twists have been given the
wires a picket 5 is dropped down between

the separated strands until its lower end rests on the foot-gage. The twister-heads are again rotated a few times, preferably in a reverse direction, and a second picket inserted and 5 the operation continued in this manner until the entire fence is completed.

The machine is very light in weight, and it is entirely supported by the fence-wires, thus requiring no track or other support, and the 10 operation of twisting the strands feeds the machine along as each picket is inserted, while the tension devices retain the proper strain on the fence-wires and at the same time compensate for the wire taken up in the 15 process of twisting.

The accompanying drawings show my invention in the best form now known to me, but many changes in the details might be made within the skill of a good mechanic 20 without departing from the spirit of my invention as set forth in the claims at the end of this specification.

Having thus fully described my invention,

what I claim as new and useful, and desire to secure by Letters Patent of the United States, 25 is—

1. In a wire-fence machine, the combination with the twister-head 4' formed with the radial lug 4¹⁰ and the longitudinal lugs 4¹² 4¹³, of the bevel-gear 8, formed with recess 8' 30 and adapted to be secured to said head, substantially as shown and described.

2. In a wire-fence machine, the combination with the parallel plates, the truss-braces and the bolts connecting the contiguous ends 35 of said plates and braces, of the twister-heads journaled in said plates and means for rotating said heads, substantially as shown and described.

In testimony whereof I have hereunto set 40 my hand in presence of two subscribing witnesses.

GEO. P. A. WEISENORN.

Witnesses:

J. W. POWELL,
THOMAS EGAN.
